United States Patent Office.

ELI S. BITNER AND J. B. HOPKINS, OF LOCK HAVEN, PENNSYLVANIA.

Letters Patent No. 61,798, dated February 5, 1867.

IMPROVEMENT IN HINGES.

The Schedule referred to in these Letters Patent and making part of the same.

TO ALL WHOM IT MAY CONCERN:

Be it known that we, ELI S. BITNER and J. B. HOPKINS, of the borough of Lock Haven, in the county of Clinton, and State of Pennsylvania, have invented a new and improved Hinge for Gates and Doors, which are designed to open both ways, and, by a slight modification, to doors and gates which are intended to open but one way, the hinge being designed to make the door or gate to which it is attached self-closing; and we do hereby declare that the following is a full and exact description thereof, reference being made to the accompanying drawings, and to the letters of reference marked thereon.

The nature of our invention consists in providing the staple of the hinge with a block or piece of metal rounded down to a sharp edge, and the eye of the hinge with two inclined planes meeting each other at the bottom and diverging towards the top. Upon these planes the edge-block moves up as the gate opens, and down as it closes; and it also consists in providing the bottom of the staple with a projection, and the side of the eye with a groove, so that the gate or door cannot be unhinged except in one position.

To enable others skilled in the art to make and use our invention, we will proceed to describe its construction and operation.

The plate, edge-block, and staple, are cast in one piece, the plate A being provided with four screw holes and fastened to the gate, the staple C pointing downwards, the edge B occupying the position represented in the draught. The plate E, the brace K, and the eye F, with its planes, are cast in one piece. The eye is provided with a groove, H, through which the projection D in the staple can be passed when the gate is lifted from the hinges. The planes G and G are slightly curved, so that the edge B lies evenly upon the plane in every position. The gate or door is made to close by its own weight, and will always stop when closed. The same principle can be applied to a door hinge by removing the plates A and E and extending the edged piece B and the brace K into plates with holes for screws, by means of which the staples can be fastened in proper position to the door, and the eyes to the door frames. The same hinge will thus answer for either a right or left hinge.

We claim the combination of the edge-block B, and spiral-inclined planes G G, with the projection D, and groove H, all constructed as and for the purpose described.

ELI S. BITNER,
J. B. HOPKINS.
